SPARK PLUG

José Soliveras, Jr., Los Angeles, Calif.

Application June 15, 1944, Serial No. 540,403

3 Claims. (Cl. 123—169)

The present invention relates to new and useful improvements in spark plugs, and has for one of its important objects to provide, in a manner as hereinafter set forth, a device of this character which is adapted to be expeditiously taken apart for cleaning and reassembled.

Another very important object of the invention is to provide a spark plug of the aforementioned character which embodies a unique construction and arrangement whereby breaking of the insulating core if accidentally struck with a tool or if the plug is dropped, will be prevented.

Still another object of the invention is to provide a spark plug of the character described comprising novel means for connecting a conductor wire thereto.

Another important object of the invention is to provide a spark plug of the character set forth wherein short circuiting by water, tools, et cetera, will be positively prevented.

Other objects of the invention are to provide a spark plug which will be comparatively simple in construction, strong, durable, reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in vertical section through a spark plug constructed in accordance with the present invention.

Figure 2 is a view in horizontal section through the device, taken substantially on the line 2—2 of Figure 1.

Referring now to the drawing in detail, it will be seen that the embodiment of the invention which has been illustrated comprises a metallic shell 1 having an externally threaded, reduced lower end portion 2. Mounted on the lower end of the shell 1 is a negative electrode 3. The shell 1 further includes a polygonal upper portion 4 constituting a head for receiving a wrench. The enlarged upper portion of the shell 1 is internally threaded, as at 5. Between the threaded portion 5 and the bore 6, a seat or shoulder 7 is provided in the shell 1.

Removably mounted in the shell 1 is a core 8 of suitable insulating material. The core 8 comprises, on its upper end, a ball 9 from which an integral ring 10 rises. The shoulder 7 supports the ball 9. A gasket 11 is provided between the

shoulder 7 and the ball 9. A retaining nut 12 for the core 8 is threaded into the portion 5 of the shell 1 for engagement on the ball 9, said nut encircling the ring 10. A gasket 13 is provided between the nut 12 and the ball 9.

Extending centrally through the core 8 is a positive electrode 14. The positive electrode 14 projects upwardly into the ring 10 and terminates in a ball head 15.

10 A conductor wire connected to the plug is indicated at 16. A terminal 17 connects the conductor wire 16 to the plug. The terminal 17 comprises a metallic ferrule 18 on one end portion of the conductor wire 16. Fixed in the ferrule 18 is a metallic disc 19 having an aperture therein in which the wire 20 of the conductor 16 is anchored. This anchored end portion of the wire 20 is engageable with the ball head 15. The portion of the ferrule 18 which projects below the disc 19 is split and formed to provide inwardly and upwardly turned jaws 21 which are engageable beneath the ball head 15 for detachably connecting the conductor 16 to the plug. A shield in the form of a live rubber collar 22 is mounted 15 on the ferrule 18 and engageable on the top of the nut 12 and the ring 10 for preventing the entrance of water, dirt, grease, et cetera.

It is thought that the operation of the device will be readily apparent from a consideration of 30 the foregoing. Briefly, electric current from the wire 20 flows through the positive electrode 14 and jumps to the negative electrode 3 and is grounded on the engine through the shell 1. To disassemble the plug for cleaning or other purposes, it is only necessary to unscrew the nut 12 to 35 permit removal of the core 8 from the shell 1. The resilient jaws 21 are engaged under tension beneath the ball head 15 in a manner to pull the anchored end portion of the wire 20 down tightly 40 against said ball head. To disconnect the conductor wire 16 it is only necessary to pull upwardly thereon with sufficient force to cause the resilient jaws 21 to open and pass the ball head 15.

45 It is believed that the many advantages of a spark plug constructed in accordance with the present invention will be readily understood, and although a preferred embodiment of the device is as illustrated and described, it is to be understood that changes in the details of construction 50 may be resorted to which will fall within the scope of the invention as claimed.

What is claimed is:

1. A spark plug comprising a shell including an internal shoulder, a core of insulating material removably mounted in the shell and includ-

ing an integral ball resting on the shoulder, an integral ring rising from the ball, a nut threadedly connected to the shell and engaged with the ball for securing the core in said shell, an electrode in the core including a ball head on one end projecting into the ring, and means for detachably connecting a conductor wire to the electrode, said means including a terminal comprising a ferrule mounted on the conductor wire, one end portion of said ferrule being longitudinally split, and in-turned hooks on said one end portion of the ferrule engageable beneath the ball head for anchoring the conductor wire in the ring.

2. A spark plug comprising, in combination, a metallic shell, a core of insulating material mounted in the shell, said core including an integral ring on one end, a positive electrode mounted in the core and including a ball head on one end projecting into the ring, an insulated conductor wire, a ferrule on one end portion of the conductor wire engageable in the ring, an apertured disc fixed in the ferrule, the wire of the conductor being anchored in said disc, one end portion of the ferrule being longitudinally split, and inturned jaws on said one end of the ferrule engageable beneath the ball head for releasably connecting the conductor wire to the

electrode with the wire of said conductor in contact with said ball head.

3. A spark plug comprising a shell including an internal shoulder, a core of insulating material removably mounted in the shell and including an integral ball portion resting on the shoulder, an integral cylindrical ring rising axially from the outer end portion of the ball portion, a nut threadedly connected to the shell and engaged indirectly with the ball portion for securing the core in said shell with opposed gaskets between the ball portion and said shoulder and said nut, an electrode secured in the core and having an end portion projecting into the core ring, means for detachably connecting a conductor wire to the electrode, said means comprising a cylindrical ferrule secured electrically to the end portion of said conductor wire and enterable in said core ring and having provision at its inner end for detachable holding engagement with said projecting end portion of said electrode, and a resilient rubber-like collar secured in cooperative position on said ferrule, whereby, when said ferrule is engaged with said projected end portion of said electrode, the collar is in covering and sealing contact with the outer end of the spark plug.
